(54) **DYING, WITH ALKALINE PRUSSIATES**

(76) Inventor: **Fleix Fossard**

Felix Frossard,

The schedule referred to in these Letters Patent and making part of the same, containing a description in the words of the said Felix Frossard himself, of his improvement in the process for manufacturing and dying with the alkaline prussiates.

Specifice account of an improved method or methods of manufacturing the prussiates of potash and of soda, and of a new or improved method or methods of employing the said prussiates or other prussiates of potash and of soda, with other substances or things (which will be described) and composing and fixing the elements of the prussiate of iron as a substitute for indigo in dying wool in the flock, piece, skins, piece or otherwise, also in dying silk, cotton, linen and other textile or organic substances fit for the purpose of receiving colors of a blue, blue black, black, bronze, madder, or any other colors, for which indigo has hitherto been employed as a ground-work, principal or auxiliary.

Principal articles on which my claims are founded.

1. For methods and processes for manufacturing the Prussiates of Potash and of Soda.
2. On the method of passing wool into an acid bath before fixing the oxide of iron.
3. On obtaining or fixing the oxide of iron on all textile substances by means of the decomposition of the protoxide of iron, either by caustic alkalies, carbonates, or the earthy alkaline caustics.
4. On fixing the deoxygenated oxide of iron on all textile substances by immersing them in a bath formed of the protoxide of iron, for example, in the mordant state.
5. On the means of producing, upon textile substances, an uniform oxygenation of the protoxide of iron, or an oxide more oxygenated, by means of a current of hot air blown upon them.
6. On the use of an alkaline and saforaceous bath after the dying operation, before uniting the oxide of iron with the specific acid of an alkaline prussiate.
7. On the passing of the textile substances (piece or cloth dyed by the prussiate of iron) into a bath of a soluble prussiate, after dying them.

8. On the passing of the textile substances, when more or less dyed by the prussiate of iron, either in a bath of a proto-salt of iron or a salt of iron, either the one or the other, or at once into one compound of these salts.
9. On the means of giving to textile substances dyed with the prussiate of iron a reddish-blue color peculiar to this salt when combined with a substance affording a red dye.
10. On the means of fixing the prussiate of iron or copper upon the textile substances, by way of double decomposition by means of a bath composed of a soluble prussiate and another composed of the proto-salt of iron or a salt of copper.
11. On the means of producing green dyes on textile substances by the prussiate of iron and a vegetable or mineral substance giving a yellow dye.
12. On the use of bismaric acid in the bath which gives a peculiar red to the blue, and to those which afford a yellow dye, and more particularly to the organic coloring materials in order to obtain green or black dyes by the prussiate of iron or copper.
13. On the means of producing blacks &c. on textile substances, and on fixing on them the oxides of iron and copper, before passing them into the vegetable coloring or other baths, and without putting metallic salts in these baths.
14. On the employment of baths for increasing or diminishing the intensity of color.
15. On the means of preventing the change of color on the dyed fabrics when exposed to the action of steam or air.
16. On the general employment of the constituents forming the prussiate of iron instead of the solid compound so termed, as I do not actually employ the prussiate of iron known in commerce, but manufacture its principal constituent parts, and bring them into union upon the surface of the cloth, or other textile substances intended to be dyed.
17. On the principles, the character the effects and consequent results of the preceding articles applied to the works of a dye house.

Many of the things described in the various prussips are not, strictly speaking, my invention, but I claim only the practical and special application to which I apply them.

them in the process of manufacturing the precipitate of Potash and of Soda, and of
drying by these and other substances, by the methods indicated.

Process

Manufacture of the Precipitate of Potash.

Take an open, or closed cylinder of cast iron, to which a proper agitator has been fitted, put a mixture of equal parts of animal substances (1) and potash, (the last charged with sulphate the better) having previously mixed with the potash about one part of
scraps of cast or forged iron or knuckle scales, or one half of colcother (porcide of iron)
or 2 parts of red ochre containing little lime, to 50 parts of potash.

Heat the cylinder to a low red heat and with the agitator, stir continually. The sub-
stances submitted to calcination, increasing the motion gradually during about
one hour, then stir more quickly, and when you find less resistance in the in-
terior of the cylinder, and that the movement is more easy (to this great attention
must be paid) you must then stir very quickly for about 8 or 10 minutes, for these
substances are, in general, brought to the desired state of calcination, which is evi-
denced when but little smoke is apparent. Then immediately proceed to discharge
the cylinder and to cool the calcined matter (2). When cooled, convey it to a
vessel which must only contain water enough for the first moistening, and
afterwards add the weak solution of Precipitate (arising from the weak washings
of the calcined substances) viz, about one quart to each pound of calcined
matter. Stir from the bottom of the vessel, with a rake, during the time the
calcined substance is thrown into the solution, continue this for some minutes
at different intervals, after a few hours the calcined matter, thus moistened,
must be put into a vessel charged to about one half of its height. Then admit
water for the first precip. (and afterwards use the weak solution in this reservoir)
so within about one foot of the brim. Fire must then be placed under the boiler,
and the substance be kept boiling for about one hour and a half, and during
this time the matter in the boiler must be continually stirred. After this
filter it, taking care to stir briskly during the time the liquid is taken out, to have
its deposit conveyed with it on the filter.

The calcined matter being sufficiently attenuated, take it off the filter, and put it
into another boiler when it must be boiled, the first time with water, and in the
second time with the weak solution of Precipitate.

subsequent precipitate with the weak solutions of the prussiate, for about an hour, then let it fall into another filter. The retained substance being sufficiently drained is then to be carried to a vessel where it must be washed with hot water (to obtain the weak solutions, of which mention has been made for boiling the calcined substance). — The Prussiate waters of the two boilings of the calcined matter being brought into one common solution, concentrate it in a boiler until it forms a pellicle or skin (3) on the surface of the boiling liquid, then put the solution into the crystallizer. — When the prussiate is crystallized and the solution cooled, convey the mother waters (that is to say the solution of carbonate of Potash) into a reservoir upon which a filter has been placed, on which the crystals are to be thrown and drained, afterwards put all the solution into another boiler for the purpose of being concentrated. — When the calcined substances are sufficiently washed and drained in order to obtain the required weak waters, they must be completely dried in a stove. — Having concentrated the solution of potash until it precipitates a sufficient quantity of its carbonate — the dried calcined matter kept as hot as possible, is to be carried to a vessel placed close to the boiler, which vessel is to be about one third filled. Add to it by portions, and that continually, the solution of boiling concentrated potash; mix the calcined matter with the potash as equally and quickly as possible. The liquid must be added until the calcined matter becomes sufficiently wetted. This mixture is submitted to calcination in the same manner as a mixture formed with fresh animal matters and potash, nevertheless a small quantity of good animal substance may be added (if desired) for the first operation, but not to exceed one fiftieth part in the weight of the mixture, and one tenth part for the second operation generally speaking, which is the last one.

As regards the potash from the mother waters, it will serve for an indefinite number of operations, until the whole is converted into Prussiate, but previously to that the mother waters will have passed almost entirely into the states of sub-carbonate and bicarbonate of Potash. To clean them of these salts they may from time to time be crystallized and the crystals to be employed for such purposes as may be desired; or as the crystals may be decomposed by calcination. For the second crystallization saturate boiling —

water with the prussiate of potash of the first crystallization in a boiler, and afterwards discharge it into a crystallizer, in which small lead weights are suspended by pieces of Park thread attached to sticks placed across the vessel for the purpose of obtaining the mass of crystals, and to procure them clean and large. It will be necessary to prevent the liquid in crystallizing from cooling too suddenly. The crystallization being finished take out the crystals, let them drain, and they are fit for use. The mother waters are concentrated to obtain fresh crystals.

Notes.

1. Dried blood, horns, hoofs of animals, hair, old woollen cloths, bones, and in fact all other animal substances are more or less proper for the purpose; however corrupt may be their state.
2. It is desirable that the calcined matter be thrown into water until after it has become cool.
3. The formation of a pectile is not always to be considered as a sure sign of perfect concentration, and of a fit state for crystallization. The carbonated salts vary in this respect considerably, therefore it is recommended, before putting the matter into the crystallizer, to take a little of the solution, to cool it quickly and to filter it; then to saturate the excess of potash, and add to it a little weak solution of the perchlorate of iron; and if the filtered liquid precipitates a blue substance, the solution has not yet attained the desired point; on the contrary, if it does not produce this precipitate, or in very small quantities, the work is complete.

Prussiate of Soda.

The manufacture of this salt may be carried on in the same vessels &c. as are used for the manufacture of the prussiate of Potash, and the process and proportions are the same. The soda possesses only one disadvantage; that is, it carbonates more quickly than potash.

The advantages which it offers are as follows.

11. The crystalline of artificial soda, when precipitated, compared with that

that of potash. 2° The soda does not produce the hydrosulphide by calcination, as is the case, more or less, with all potashes, in consequence of which the muriate of iron, for example, made with scales of iron, may in order to have the oxide in a state of hydrosulphide, be added to the water of the weak solutions of soda (if desired) before the calcined product is thrown into it. 3° The artificial soda is, as well as potash, the produce of our soil and of our industry.

Additional Products.

If a closed cylinder be chosen for the calcination, a tube can be adapted to the part opposite the place of insertion of the agitator, for the purpose of conducting the gaseous products into the first vessel of an ordinary Woulfe's apparatus, whence they may pass into other vessels where they may be separately collected. If the first boiler is in like manner closed and furnished, a reservoir can be appended, having an inverted leaden bell and containing a mixture of one part of sulphuric acid to ten parts of water. The gaseous products having run through will pass into the first vessel of a Woulfe's apparatus, that is into the first of two vessels placed at a little distance from the boiler, the first one being filled to about half its height with a solution of the muriate of Lime, which we will suppose to be about 15 degrees of the acetometer for salts, and the second, left entirely open, with the same quantity of water acidulated with sulphuric acid, as above. The products obtained are: 1° Hydrogen gas, This gas may be employed to light the establishment, or for any other purposes. 2° Sub-carbonate of ammonia. This salt obtained in the Woulfe's apparatus is deposited in a reservoir, on taking the solution of the nearest vessel to the cylinder. That in the second must be put into the first, and that of the third into the second, taking care always to put water into the third, thus the solutions will be successively deposited in the reservoir. After some hours of repose, the colored ammoniacal solution may be drawn off, and when it is perceived that the evaporation begins to stop,

you collect it. 3rd. Emphyreumatic Oil. This oil may be employed with the calcined matter (produced by the first calcination) instead of mixing it with solid animal substances, as it answers quite as well as the best of these substances. 4th. Sub-carbonate of ammonia. This salt is heated by the process already known, and used for its ordinary purposes. 5th. Nitrate of ammonia. This salt obtained in the two vessels of the apparatus requires only to be collected and sublimed to obtain the salt in its ordinary form.

General Observations

Great advantages will arise if the divers reservoirs &c are made of metal; Cast iron in preference to all others, as those constructed with wood do not answer so well. The utmost rapidity is required in charging the cylinders, so that the materials remain as short a time as possible without being agitated; and also in discharging it, so that the calcined matter may be withdrawn from the cylinder as soon as it has arrived at the proper point; at that point the matter will be of a pluming nature somewhat like the mortar used by masons:— if notwithstanding this state of semi-fluidity, small or lifting appearances of smoke should proceed from it, this will not be an unfavorable circumstance. This semi-fluidity will never take place if a sufficient quantity of potash has not been employed; therefore care should be taken to apply rather an excess of alkali, because that part of it, which is not converted into potassium, will not be lost:— experience will prove the best guide on this subject. The work of calcination once commenced should be continued night and day for the sake of economy, and conducted in the same manner, with this only difference, when the mixture is made of animal substances which have already been employed: the operation is more prompt, and it will not be necessary to add any, or at all even to but a small quantity of the foregoing substances. Pumps and channels should be employed to transport the liquids from one vessel to another because they can be transported infinitely more quickly and without the waste occasioned by transporting them by hand.

The reservoirs should be about eight high.

Laying Principles.

Baths.

- 1st. Acid Bath. This is composed of one part of the sulphuric acid of ordinary strength (1) and about 50 parts of water, and is to be employed at a temperature of from 77 to 100 degrees $^{\circ}\text{F}$. or thereabouts. 2. Alkaline Bath. One part of carbonate of soda and 100 parts of water, 77 to 100 degrees $^{\circ}\text{F}$. 3. Alkaline Bath (2) Carbonate of soda of the specific gravity of three degrees by Beaumis arcometer for salts - 77 to 100 degrees $^{\circ}\text{F}$. 4. Ferruginous Bath. All that will be said of this bath in respect to its state of composition, excepting as regards specific gravities, is to be understood as applying also to the other baths formed of the protoxide of iron, such as Nos. 5 and 10, in every instance where the contrary is not mentioned. Protoxide of iron (3), as for instance the neutral proto-muriate (4) at about 6 degrees of the arcometer - 100 to 105 degrees $^{\circ}\text{F}$. 5th Protexided ferruginous bath. Protoxide of iron of little specific gravity, which may be so small as to be nearly insensible to the arcometer (5) about 100 to 105 degrees $^{\circ}\text{F}$. 6. Alkaline Bath. Alkali, for instance, one part of carbonate of soda to about 100 parts of water - to be employed as no. 2. 7. Carbonated Saponaceous Bath. Soap, for example, neutralized 1/3 of the specific gravity of about 1/2 of a degree of the arcometer - 212 degrees $^{\circ}\text{F}$. 8. Prussiate Bath. Prussiate of Potash (6) and sulphuric acid (3) in such proportions as may be required to vary the tinge of color which is required to be given to the substances intended to be dyed - 122 to 140 degrees $^{\circ}\text{F}$. 9. Prussiate Bath. To be used according to circumstances: the same prussiate as in No. 8, at about one degree of the arcometer - 132 to 140 degrees $^{\circ}\text{F}$. 10. Protexided ferruginous bath. Protoxide of iron (3) at about 1/4 degrees of arcometer for salts - 190 to 210 degrees $^{\circ}\text{F}$. 11. Perminated ferruginous bath. One of the per salts of iron at about 1/4 degrees of the arcometer. It will be used with the proto-muriate of iron which has been oxygenated, for example, with the Chloride of Lime (7) at about 192 to 210 degrees $^{\circ}\text{F}$. 12. Acid Bath. Water slightly acidulated with muriatic or any other acid which will be found equally good, except nitric acid, which tinges the wool yellow - 100 to 105 degrees $^{\circ}\text{F}$. 13. Cupaceous Bath. Either muriate or any other salt of copper at about three degrees of the arcometer - 132 to 140

described or those above. 14. Ammoniacal bath. Liquid ammonia to be employed in proportion varying according to the color required to be given to the cloth etc. — but in general in the following proportions — about one part of the ammonia in volume to 300 parts of water. This bath is generally made and used at the ordinary temperature, either to saturate the excess of acid in the cloth etc. and regulate and augment the intensity of the blue. 15. Aluminous caligin bath. A mixture of alumine, or lime, at about 100 degrees of the asconite, or a little less, in water charged with an earthy carbonate such as lime 8% — this bath to be employed at about 132 to 144 degrees. 16. Red Bath (16). Made by the ordinary method, but before employing the bath it should be made slightly acid by means of Boracic or other suitable acid (11). 170 to 200. 17. Yellow Bath. Thread (22) or any other yellow coloring material — at about 170 to 212 degrees. 18. This bath may be prepared with any of the substances containing gallic acids, and with lignwood, Brazil wood, or any other materials generally employed to dye black, brown, or Maroon colors — 167 to 190 degrees. 19. Hot Stove Bath. A temperature of from about 132 to 144 degrees will generally produce the same action on metallic colorants as a liquid bath; for example, when a current of warm air has been introduced on the textile substances (13) either when they contain a protoxide of iron which passes to a higher state of oxygenation, or when the said textile substances are impregnated with a proto-salt of iron which is decomposed by the super-oxygenation of its oxide, or in fact by oxygenation or de-oxygenation, as it will be understood that the blue prussiate of iron is a proto-bi-cyanate in reference to the white prussiate of iron obtained by decomposing an alkaline prussiate by a proto-salt of iron; or that the blue color is a cyanate of iron, or either the one or the other. Therefore, whenever the fabrics or other substances are in either of these three conditions, and when they are exposed to a current of air peculiar to this operation, it will be called the hot stove bath. 20. Ammoniacal vapor bath. The exposure of the cloth or other textile substances or materials aged by the protoxide of iron to an ammonia vapor bath gives the protoxide of iron an intensity of color, and strength, depending on the quantity of the existing matter etc.

at the ordinary temperature. 21. Acid vapor bath. The exposure of substances or materials dyed by the prussiate of iron to an acid bath, either sulphuric, muriatic, acetic, &c., causes the intensity of color produced by the ammoniacal vapor by soap 4%, to be lowered, or to become of less intensity - at an ordinary temperature, or from that to any other approaching 100 or 190 degrees if desired. — The baths 1, 2, 5, 6, 7, 9, and 10, 12, last but little, and may be continued in use for about 15 days or even much longer. Bath No. 9 will be serviceable for about a month, if the wools are well freed from grease, and washed, before being submitted to this bath; under all circumstances it will be quite fit for use until it becomes soapy and dirty; in that case those qualities would appear on the wools on being taken out of the bath. Nos. in this state 14, 3, must be considered as waste. The bath No. 4 should indicate about 5 or 6 degrees of the anerometer for salts; having become alkalinized by decomposition of 4 or 5 degrees of Alkline salt, it indicates, in the whole, 10 or 11 degrees and becomes unfit; in that state, it may be employed, if desired, to form the bath No. 10, or above all others, that of No. 11. Bath No. 8 will serve for 8 or 10 operations for wool in the grease and for 2 or 5 operations for cloths in the piece, or wool in the skins, or other substances; this difference arises only from the circumstance of our being enabled to put more of the prussiate of potash in the bath, when operating on the last articles, as a less quantity of raw wool can be placed in the vessel, than of the wrought material. The prussiate bath No. 9 is never to be thrown away, whatever may be its specific gravity, it will always serve to form the bath No. 8 on adding acid to it. If it be too strong of prussiate, add water, if too weak add prussiate. Bath... 19 as ^{no} 4. Bath No. 14 will serve for 20 or 30 operations, and after that will be useful in forming the bath No. 8, instead of employing water and prussiate. As regards the other baths, it may be generally said that they continue useful for the same time as baths in ordinary use among dyers, notwithstanding it may be proper to state, that as they are not so likely to become agitated or unsettled as common baths, their useful qualities may be extended over a longer period.

The process for dyeing the different materials being the same, the operation differs only in the manner of handling them, which manner these various kinds well suggest: I will take, for example, wool in the fleece or flock. It is to be observed that only the woollen materials require the bath No. 1 and 2. Put into the bath No. 1, wool which has undergone the first operation of being freed from grease, allow it to remain about 10 minutes, stirring it for a short time. When it is taken out, if the liquor which drains from it be sensibly acid to the taste the operation is thus far accomplished. If on the contrary it be not, add a little acid to the bath and repeat the operation. When drained introduce it into the bath No. 2, and treat it in the same manner and during the same time as No. 1. The liquor which drains from the wool on its being withdrawn from bath No. 2, should have an alkaline taste. Whatever may be the nature of the wool submitted to these two baths or at least to the first one, it will absorb a much greater quantity of the oxide of iron than if it had been prepared by any other method, and after the oxide has been saturated by means of Prussian acid, the cloth will preserve its color during the operation of finishing, and in its general wear and usage.

The general method of fixing the oxide rests on two grand principles which we distinguish by the names of first and second methods. The first method is that of giving the proto-oxide of iron on the wool by means of the decomposition of the proto-salt of iron by alkalies, or by their alkaline carbonates, or by caustic earthy alkalies. The second method is founded on the general nature or quality of the oxide of the proto-salt of iron, a portion of which is constantly oxygenated when it comes in contact with the air, and when it abandons or throws off a part of its acid, and by this abandonment causing a much greater degree of oxygenation, and thus fixing on, and impregnating the wool with this salt, when this chemical change takes place. . . . . .

Third method of fixing the Oxide of Iron.
The wool having been prepared by the bath No. 1, washed and drained, or even dried, will be put in bath No. 3 and stirred for a short time. When taken out, and drained one hour, place it in the bath No. 4. The small quantity of wool which is not perfectly drained should be squeezed, or pressed,

wring, before it is put into the bath. Take care to spread the wool as evenly as may be in the vessel in order that the mordant may be equally diffused to prevent an irregularity of color. One workman must continually agitate the surface of the bath with a stick in order to submerge the wool, and he should be careful not to scratch well to the bottom of the vessel until it has been well bathed in the liquid. Once or twice during this operation it may be well to discontinue putting wool into the bath, for a few seconds, during which time the wool already in the bath should be well turned round from top to bottom. This operation is more for the purpose of agitating the liquid than for any thing else, by which means the same quantity of the ferruginous matter continues to be applied upon the surface of the wool as at the commencement of the operation:— After having thus turned the wool over continue to add more of it, whilst ever you find it sinks into the vessel without progress. After having remained in the bath for about four of an hour, take it out, drain it, and a few minutes afterwards convey it to the warm stone bath No. 9, in an ordinary stove; but a current of air heated and forced into it, is preferable to that of a natural circulation. The oxide being sufficiently oxygenated, the wool is to be removed to another bath, suppose No. 5, having remained and been stirred in this for about 5 minutes, it is taken out, drained and conveyed to bath No. 8, where nearly the same course must be followed as with No. 5. When it is desired to obtain a greater intensity of color from the oxide of iron, the wool must be re-peated several times into the baths No. 3, 4, 5 and 6, and probably a few more inserted into No. 8 and No. 9, may be requisite than into the others. Many things in fact, relating to this method, depend on the color of the oxide which it is desired to obtain, for example, if you desire to have a color less intense, make an alkaline bath of less strength, or conduct the process of applying the mordant by the second method, or employ the baths generally less strong, or do not make use of the hot stone bath &c.

Second method.

The principal difference in this method from the first one, is that the bath No. 9 is not employed, as for this is substituted the immersing the wool, more or less,

in the bath No. 4, and also the use of baths rendered neutral by means of the earthy alkaline carbonates. These baths are called neutral earthy baths. The oxide of iron will become fixed on the textile substances by repeated immersion in the bath No. 4 or any other bath containing the proto salt of iron and a neutral earthy carbonate. If necessary, saturation of the iron of acid (set at liberty by the oxide being fixed on the wool) may be repeated, after every immersion (except after the first one, because the bath will remain in a neutral alkaline state, if the work has been conducted by the mode recommended for the first method) for example, until the bath forms a fullicle on its surface, which will be perceived in blowing on it. It will appear milky on adding chalk to it, but become perfectly clear on being filtered; if too great a quantity of the carbonate of lime has not been put into it.

The mordant being applied to the wool by either of these methods, and the wool stained, or dried which is preferable, put it into the sepiaceous bath No. 5 in the following manner. Put about one third part of the wool which has been removed from bath No. 4, scattering it about as much as you conveniently can, by handfuls at a time, stir it about continually whilst it remains in the bath, and after having remained there for 2 or 3 minutes take it out, drain and wash it in plenty of water.

Dying in Blue with the prussiate, or saturation of the oxide of iron by means of Prussic acid.

The bath No. 8 should be prepared, in the following manner for (we will suppose) 100 pounds of wool mordanted for a royal or dark blue color (the cloth being nearly in a finished state) with 10 pounds of Prupiste of Potash or of Soda and about 10 pounds of sulphuric acid (if that acid is chosen) mixed together in about 100 gallons of water. Put all the wool quickly into it, then stir it at intervals of about ten minutes. The operation will be complete in about an hour and a quarter, if it should not be necessary to add either one or the other of the two articles with which the bath is formed; if such should be the case, the wool must be entirely withdrawn out of the bath, while such addition is made, and immediately afterwards be quickly lowered into it. An excess of the substance forming

forming the bath may always be left in it, and, in general, it will be found more convenient, in case you are dying wool, as in this instance, in the fleece or flock, than may be found necessary when you are operating on cloths or stuff, but above all it will be found so if the mordant has been applied on the wool, which wool having been woven, you are unwilling to discolor, or obscure the lists, marks or figures, and where it is intended to pass the same into baths No. 10 and 11. The wool being now in a colored state, the operation of dying may be continued by the manipulations and processes which follow, and which may be termed variations, by passing it successively into baths No. 10 up to No. 20 as may be requisite. The following are examples of some of these variations. 1st. The wool may be left in the state in which it was withdrawn from bath No. 9. 2nd. It may be dipped into bath No. 9 for about 5 minutes, drained, and put into bath No. 10 for a few minutes, then immersed so as to suppose in bath No. 10 two or three times in quick succession and withdrawn. 3rd. After bath No. 9, bath No. 13 may be resorted to, instead of No. 10. 4th. Instead of bath No. 12 after No. 10, No. 11 may be previously employed. 5th. On the wool being withdrawn from the principal baths, 8, 10, 12 and 13, it may be carried to the warm stove in order to exogenate and augment the intensity of the prussiate of iron. 6th. After this the baths from 8 to 9, 10, 11, 12, 13, 14, 15, 16 can be resorted to for about $\frac{1}{2}$ of an hour, and the wool, when drained, be conveyed to No. 16 for about 12 or 15 minutes. 7th. Bath No. 15 can be omitted and the wool passed simply in No. 16 as the one intended to produce a reddish hue upon the blue $\frac{1}{2}$. After these various manipulations the wool is to be washed in plenty of water, then to be dried in order that it may be finished or brought into the required state to be woven into cloths $\frac{1}{2}$.

Black, Bronze, &c, colors.

These various colors may be obtained in the following manner. When you have affixed one or more of the metallic oxides on the textile substances, by the means already pointed out in reference to bath No. 10 B, you may (by means of the action of the gallic substance, logwood, Brazil wood, or other vegetable colorants for coloring these dyed) form these different colors

colors and shades, on putting the textile substances into them at about 150 to 165 degrees Fahr. and afterwards applying the Prussianic of iron by the use of baths 9 and 10, more or less concentrated. For dying cotton of a black, which will resist the action of the air, and the effects of washing, proceed as follows. 1°. Suppose bath No 3 to be made with the caustic earthy alkalies, with lime for example, and at 77 to 100 degrees. Instead of bath No 4, employ No 13 which we will suppose to be made with the dextro-muriate of copper, and only indicating about half a degree of the anerometer for salts, if the bath No 3 has been formed and employed as before named taking care that it be limpid when the skins are plunged into it. 2°. The skins may be plunged into milk of lime, but in that case ^{the bath} No 4 or 13 must be more strongly charged with metallic salts. 3°. In fact, whatever may be the nature of the lime bath, several immersions must be made from 3 to 4 or 13 and vice versa, until the desired quantity of the oxide of copper is distributed over the fibrous substance. 4°. In the application of the salts of copper as a mordant, the bath No 2 properly called alkaline may be employed instead of the caustic earthy alkaline, but above all when the bath is used at the ordinary temperature. 5°. A bath may be formed alone of the salts of copper and of iron. The mordant being fixed the cotton must be passed in the proper baths to produce a black dye (14).

The hair of different animals, and other substances which are used for making cloth or other fabrics, but which are generally filled, may with facility, be dyed of the different colors which have already been spoken of, in respect to other textile substances, after having been mordanted as already described. In fact, all organic substances, such as straw, wood, &c. may be dyed by the processes and means before stated, soled referring to the baths, &c.

6°. Almost all the acids, except sulfuric acid, are fit for the formation of this bath. 2°. Soda, flesh, or ammonia, either caustic or carbonated are fit for this bath, but the carbonates are preferable, and the carbonate of soda is recommended in preference to all others. The earthy carbonic

alkalis may also be used to form this bath and no. 6. In composing these baths with earthy alkalies, a larger quantity of them must be introduced, than of Potash, Soda, or ammonia, because they do not contain the same degree of alkaline properties; and the vessels in which the baths are formed, must be deeper in order to contain an excess of alkali, and the baths must not be raised to quite so high a degree of heat.) 3rd; all the proto-salts of iron are more or less useful to form this bath which must be rendered neutral;—this may be done by adding the carbonate of lime, until the formation of a pellicle on the surface, which will be ascertained by blowing on it. 4th; The homogeneous baths rendered neutral by caustic or carbonated alkalies are called neutral alkaline baths, and those rendered so by caustic or carbonated earthy alkalies, are called earthy neutral baths.) 5th; This bath may be formed with the water into which the clothes, wool, &c. have been passed after being withdrawn from bath no. 4, as it will be found that a sufficient quantity of the proto-salt of iron has been deposited, for the required purposes.

6th; Neutralized by a well carbonized alkali, for example, Soda the alkaline principle of which represents about one half, of the same principle of which the Soda is composed. Instead of soap, the alkali may be saturated by oil, greases &c. In fact all the alkalies saturated by a greasy matter will answer the purpose, particularly if a small portion of it remains in excess in the bath.) 7th; all the Prussiates, alkaline as well as earthy, and above all that manufactured by the preceding process, will be found more or less useful for this bath and no. 9. 8th; all the acids which in coming into contact with the articles named in the preceding note, will cause the prussiate of iron, will be found more or less fit for the formation of this bath.) 9th; see note respecting bath no. 4.

9th; All sorts of chlorides will be found good for the purpose of oxygenating the proto-salt of iron, and to keep it in the state already indicated. 10th; all the coloring matters, either vegetable or animal, will be found useful for that bath.) 11th; Boracic acid, without taking out the alumina of the mineral mass, will produce a sensible change or alteration of Prussiate of iron.

now in the bath. 10th. Boracic acid, may also be added to the yellow vegetable coloring bath, in order to produce various shades of green by the use of the prussiate of iron. 11th. A Prussiate of copper may also be obtained by double decomposition as a substitute of the prussiate of iron, 12th. For several years past various cloth manufacturers have pursued a new process in their works, which they have denominated "Decatipage" or sponging; its intention is to prevent the cloth from being spoiled by rain &c. — this process is performed upon the cloth in different stages of its manufacture, and also at the last and finishing one, when it is fitted to be made into garments. This operation has sometimes the apparent inconvenience of changing or modifying the clearness and beauty of the color of the prussiate of iron upon cloths upon which it is applied; but this change is effected without decomposing the blue, — its natural beauty retains on exposing it to the air, and especially to a humid air, to water, or to a liquid alkali, or to ammonia more or less dry. If the dye upon the cloths &c. is perfect in color, this change will be produced in a less degree. It should be remarked, that the cloths very old garments resist the action of steam more perfectly than those of cloths which have been recently finished, and upon which the air has acted for a short time only. This valuable property of acquiring fixidity by the action of the air is, for the dye by the prussiate of iron, a character entirely different from the radical defect of the dye by indigo, the color of which is partially destroyed from the moment it is exposed to the action of the light or air, and which also becomes white by friction.
